UNITED STATES PATENT OFFICE.

ALBERT FREDERICK PETITHORY, OF PHILLIPSBURG, NEW JERSEY.

TENSION DEVICE FOR SHUTTLE.

1,113,045.

Specification of Letters Patent.

Patented Oct. 6, 1914.

Application filed April 23, 1913. Serial No. 763,134.

To all whom it may concern:

Be it known that I, ALBERT F. PETITHORY, a citizen of the United States, residing at Phillipsburg, in the county of Warren and State of New Jersey, have invented new and useful Improvements in Tension Devices for Shuttles, of which the following is a specification.

This invention relates to tension devices for shuttles.

An object of the invention is to provide a tension device for use in place of the fur commonly employed to grip the filling or tram as it leaves the quill to apply a tension or retarding motion to the tram to operate the tension ring, whereby the fur may be dispensed with and a more reliable and efficient tension obtained.

A further object of the invention is to provide a tension ring of such construction that any ring section thereof, when worn or damaged, may be readily replaced by a new one.

The invention consists of the features of construction, combination and arrangement of parts hereinafter fully described and claimed, reference being had to the accompanying drawings, in which:—

Figure 1 is a plan view, partially in section, of a shuttle embodying my invention. Fig. 2 is a vertical section taken on a line passing through the primary tension device. Fig. 3 is a detail view of the primary tension device removed. Fig. 4 is a horizontal transverse section through the shuttle, showing the tension ring. Fig. 5 is a detail section through the tension ring.

Referring to the drawing, 1 designates the shuttle body, 2 the bobbin, and 3 the bit or cavity in the body occupied by the bobbin. The filling, tram or weft 4 passes, in the construction shown, from the bobbin through a primary tension device 5 at the forward end of the bit, thence through a guide passage 6 into a chamber or recess 7 at the forward end of the body, thence through the tension ring 8 and finally out through guide spaces formed by a series of pins or spacing members 9.

The primary tension device 5, which is designed to exert a retarding action on the thread, to effect the action of the tension ring 8, is constructed in accordance with my invention of a substantially U-shaped frame 10, stamped or otherwise formed from a single piece of metal. The top or cross

portion of this frame 10 is secured to the shuttle body by suitable fastening devices 11, and the sides of said frame are provided with inclined slots 12 in which are slidably and revolvably mounted a pair of tempered steel friction rollers 13. The weft 4 passes between these rollers which are revolved thereby and exert a frictional pressure thereon to retard the weft on its passage, thus adapting it to impart a tensional pull to the tension ring 8. The ring 8 is constructed, in accordance with my invention, of a flat steel plate 14 having at one end a crank arm 15 pivotally mounted upon a pin 16, said crank arm being acted upon by a coiled spring, elastic band or like element 17, whereby the tension ring is held in normal position. Carried by the plate is a series of tension or guide rings 18 through which the tram passes. Each of these rings is constructed of a piece of spring metal bent to form a ring or eye portion and having its extremities bent to provide hook-shaped spring arms 19 engaging alined transverse notches 20 in the side edges of the plate 14. Each eye or guide ring is thus independently mounted and applicable and removable at will, so that in the event of any ring becoming worn or broken it may be removed without disturbing the others, and without the necessity of discarding the tension device as a whole. It will, of course, be understood that in applying or removing a ring the arms thereof are spread apart, and that when placed in position for application, the arms upon being released will snap into engagement with the notches.

From the foregoing description, the construction and mode of operation of my improved tension device will be readily understood, and it will be seen that it provides a primary tension device which obviates the necessity of employing the fur commonly used, and avoids the objections incident thereto. It will also be seen that the invention provides a tension ring having detachable ring members which are readily removable in case of wear or breakage, thus enabling them to be conveniently replaced with new ones, without the necessity of discarding the entire ring member, as is necessary in the use of tension rings having fixed rings or eyes.

I claim:

In a shuttle, the combination with a shuttle body, having a bobbin chamber and a

recess in communication therewith through a restricted guide passage, a bobbin mounted in said bobbin chamber, and a secondary tension device arranged within the recess 5 for action upon the thread passing from the bobbin through said guide passage, of a primary tension device arranged between the bobbin and guide passage, said tension device comprising a frame having side walls 10 provided with slots inclined at an angle to

the line of travel of the thread, and tension rollers revolvably mounted in said slots to engage the thread between them.

In testimony whereof I affix my signature in presence of two witnesses.

ALBERT FREDERICK PETITHORY.
